Assistant Examiner — Margaret Leah Bryan

CLAIM

The ornamental design for a back scratcher as shown and described.

DESCRIPTION

The file of this patent contains at least one drawing/photograph executed in color. Copies of this patent with color drawing(s)/photograph(s) will be provided by the Office upon request and payment of the necessary fee.

1.1 Front

1.2 Left

1.3 Right

1.4 Bottom

1.5 Top

1.6 Back

1.7 Perspective

1.8 Perspective

It is a back scratcher which is used to scratch areas that are hard to reach on the back.
